UNITED STATES PATENT OFFICE

2,241,490

PUZZLE

Irving Steinhardt, New York, N. Y.

Application March 30, 1939, Serial No. 264,882

8 Claims. (Cl. 273—160)

This invention relates to amusement devices such as puzzles, and more particularly to puzzles of the take-apart and put-together type.

One object of this invention is to provide a puzzle of the class described which is composed of a relatively small number of puzzle pieces but which, nevertheless, is sufficiently difficult to solve to sustain interest therein.

Another object of the invention is to provide a puzzle of the type referred to which comprises puzzle pieces of simple geometrical configuration and which, when put together, form a pleasing geometrical design.

Another object of the invention is to provide a puzzle which can be designed to provide a varied degree of difficulty in solving the same, without changing the number of puzzle pieces or the geometrical configuration thereof.

The above objects of the invention and other objects which might hereinafter appear will be fully understood from the following description considered in connection with the accompanying drawing, which, however, is to be considered only as illustrative of the invention and not in limitation thereof.

In the drawing:

Fig. 1 is a plan view of the puzzle pieces at one side thereof in put-together relation;

Fig. 2 is a view similar to Fig. 1 showing the other side of the puzzle pieces;

Fig. 3 is an end view in elevation of one of the puzzle pieces;

Fig. 4 is a sectional view on the line 4—4 of Fig. 1; and

Fig. 5 is a sectional view on the line 5—5 of Fig. 1.

Referring now to the drawing in detail, the puzzle embodying the present invention comprises, as here shown, three elements or puzzle pieces 1, 2, and 3 respectively which, when the puzzle is put together, as illustrated in Figs. 1 and 2, are in intersecting and interfitting or mutually overlapping relation in the same plane. Each of the said elements is preferably, but not necessarily, in the form of a ring-shaped member and may be made of any suitable material such as, for example, wood, metal, "Bakelite" or other synthetic resins, Celluloid, cardboard, paper pulp, etc. These ring-shaped members are preferably of the same size and each is defined by an annular rim 4 of suitable width and thickness, said rims of the several members being preferably of the same width. The rim 4 of each of said members is provided with a plurality of grooves extending completely across the rim

from the internal periphery to the external periphery thereof, thereby forming circumferentially extending portions of reduced thickness so that when the puzzle pieces are properly assembled, predetermined grooved portions of the three members interfit in such manner that the three annular members are held by each other against relative displacement in their own planes, but are readily separable from each other by relative movement thereof in a direction transverse to said planes. Also the grooves are preferably of such depth that when the three annular members are put together properly in the solution of the puzzle, they are flush with each other at both sides of the assembly. These grooves and other grooves with which each of said annular members is provided will now be described in further detail.

As illustrated in Fig. 1, the rim 4 of annular member 1 is provided with circumferentially spaced grooves 5, 6, 7, and 8, in which are received correspondingly grooved portions of annular members 2 and 3, grooved portions 9 and 10 of member 2 being interfitted with grooved portions 5 and 7 of member 1, and grooved portions 11 and 12 of member 3 being interfitted with grooved portions 6 and 8 of member 1. Annular member 2 is provided with grooves 13 and 14 in which are received the grooved portions 15 and 16 respectively of annular member 3. Each of said grooves has spaced opposed arcuate edge walls indicated by way of illustration at 5a and 5b in reference to the groove 5 of annular member 1, it being understood that all of the grooves have similar opposed arcuate walls and that the latter correspond in curvature to that of the inner and outer peripheral edges of the rim of the annular member. Thus, each groove has a width substantially equal to the width of the rim 4, being but slightly wider than said rim so that the grooved portion of one rim fits snugly within the companion groove of the companion interfitting rim. In other words the opposed edge walls of the grooves have arcs of curvature the radii of which equal to the inner and outer radii, respectively, of the rim 4, and the centers of curvature of said arcs are all located at the outer periphery of the rim. This applies to all of the grooves including those to be hereinafter described. The depth of each groove is preferably such that when the puzzle pieces are put together they are flush with each other at both sides of the assembly. Figs. 4 and 5 illustrate the interfitting relation of companion grooved portions of two members. All of the

other companion grooved portions similarly interfit.

In accordance with the present invention the arcuate grooves 6, 8, 13, and 14 in the ring members and the corresponding grooved portions 11, 12, 15, and 16 are located in the several annular members in such manner as to add to the difficulty of putting the parts together in solving the puzzle. This is accomplished by locating the center of curvature of the arcuate edges of said grooves at a point "A" on the outer periphery of ring member 1 displaced circumferentially from the point of intersection "B" of the peripheral edges of annular members 1 and 2, whereby the cord "C" of the subtended arc corresponding to the inner arcuate edge of rim 4 of member 3 between grooved portions 15 and 16 is less than the cord "D" of the subtended arc on the inner arcuate edge of the rim of member 2 between the grooved portions 9 and 10 thereof. Cord "E" of the subtended arc of the inner edge of the rim between the grooved portions 11 and 12 of member 3 is equal to cord "D", so that cord "C" is, of course, smaller than cord "E".

Further to prevent a too ready solution of the puzzle, each of the puzzle pieces is provided with additional grooved portions in one or both sides thereof providing false clues to the solution of the puzzle. Thus, as shown in Fig. 1, member 2 is provided with grooves 17 and 18 having opposed arcuate edges 17a, 17b and 18a, 18b, respectively, of which the center of curvature is located at point "F" on the edge of rim 4 of member 2. Member 3 is provided with grooved portions 19 and 20 having opposed arcuate edges 19a, 19b and 20a, 20b, respectively, having their center of curvature located at point "G" on the outer periphery of member 3. Additional grooves 21 and 22 are provided in member 3 and these grooves have opposed arcuate edges 21a, 21b and 22a, 22b, respectively, the center of curvature of which is located at the point "H" on the outer periphery of member 3. Member 1 is provided with grooved portions 23 and 24 on the side of said member opposite that provided with grooves 5, 6, 7, and 8. The arcuate edges 23a, 23b and 24a, 24b have their center of curvature located at the point "I" on the outer periphery of member 1. Member 1 is also provided, in said last mentioned side thereof, with grooves 25 and 26, having arcuate edges 25a, 25b and 26a and 26b having their center of curvature located at the point "J" on the outer periphery of member 1. The rim 4 of member 2 is also provided with additional grooves in the side thereof opposite the side illustrated in Fig. 1, these additional grooves being indicated at 27 and 28 in Fig. 2. The arcuate edge walls 27a, 27b and 28a, 28b, respectively, of grooves 27 and 28 respectively, have their center of curvature located at the point "K" on the outer periphery of member 2.

It will be understood that the grooves in the several puzzle pieces 1, 2, and 3 are so located and designed, for example, as hereinabove described, that said puzzle pieces can be assembled in mutual interfitting or put-together relation, that is with one of the puzzle pieces intersecting both of the other puzzle pieces only in one relative position of the three puzzle pieces. Further it will be understood, however, that any two of the three puzzle pieces can be interfitted in several relative positions of said puzzle pieces. By reason of this feature, the worker of the puzzle, if he is not careful, is apt to make one or more

false starts towards the solution of the puzzle. Thus, for example, puzzle piece 2 can be interfitted with puzzle piece 1 when the grooved portions 9 and 10 of puzzle piece 2 are interfitted with the grooved portions 6 and 8 of puzzle piece 1, but when these two puzzle pieces are thus interfitted, it is impossible to assemble puzzle piece 3 in interfitting and intersecting relation with said two puzzle pieces. Similarly, puzzle piece 3 can be interfitted with puzzle piece 1 in grooves 5 and 7 of the latter, but when these two puzzle pieces are thus interfitted, it is impossible to assemble puzzle piece 2 in proper interfitting relation with both puzzle pieces 1 and 3. It is also possible to interfit puzzle piece 3 with puzzle piece 2, for example, in grooves 9 and 10 of said last mentioned puzzle piece, but when these puzzle pieces are interfitted in this manner, it is impossible to interfit puzzle piece 1 in proper relation to both of puzzle pieces 2 and 3.

Thus, it is seen that the puzzle herein shown and described is well adapted to accomplish the several objects of the invention. It will be understood, however, that certain changes in the construction and arrangement and form of the parts may be made without departing from the underlying principle of the invention. Thus, for example, the puzzle pieces may be in the form of discs instead of open rings as illustrated, in which case, the arcuate grooves will extend continuously from a point at the outer periphery across the face of the disc to a correspondingly circumferentially spaced point on the outer periphery of the disc. Other changes, modifications, and adaptations will occur to others in view of the present disclosure. Therefore, I do not wish to be limited precisely to the form of the invention as herein shown or described except as may be required by the scope of the appended claims.

Having thus described my invention what I claim and desire to secure by Letters Patent is:

1. A puzzle of the put-together type comprising a plurality of flat puzzle pieces each of which is a ring shaped member having a radially extending peripheral rim, the rims of said members having interfitting portions in releasable engagement with each other, said pieces in the put-together positions thereof being disposed in mutually overlapping relation in the same plane.

2. A puzzle of the put-together type comprising a plurality of flat puzzle pieces each of which is a ring shaped member having a radially extending peripheral rim, the rims of said members having interfitting portions in releasable engagement with each other, said pieces in the put-together positions thereof being disposed in mutually overlapping relation in the same plane, said interfitting portions comprising grooved parts each of which is defined by opposed arcuate walls.

3. A puzzle of the put-together type comprising a plurality of puzzle pieces each of which is a ring shaped member having a radially extending peripheral rim, the rims of said members having interfitting portions in releasable engagement with each other, said pieces in the put-together positions thereof being disposed in mutually overlapping relation in the same plane, said interfitting portions comprising grooved parts each of which is defined by opposed arcuate walls the radii of curvature of which are substantially equal to the radii of the inner and outer peripheries of the rim in which said grooved parts are located.

4. A puzzle of the put-together type comprising a plurality of puzzle pieces each of which is a ring-shaped member having a peripheral rim of radial extent, the rim of each of said members having spaced grooves extending transversely thereof, each of said grooves having opposed arcuate edges defined by the arcs of radii which are substantially equal to the radii of the inner and outer arcs, respectively, of the rim in which said grooves are located, said puzzle pieces interfitting with each other in intersecting relation of the ring-shaped members when certain of the grooved portions of one of said members interfit with certain grooved portions of another of said members, there being at least three of said members disposed in mutually overlapping relation in the put-together position of said pieces.

5. A puzzle of the put-together type comprising a plurality of puzzle pieces each of which is a ring-shaped member having a peripheral rim of radial extent, the rim of each of said members having spaced grooves extending transversely thereof, each of said grooves having opposed arcuate edges defined by the arcs of radii which are substantially equal to the radii of the inner and outer arcs, respectively, of the rim in which said grooves are located, said puzzle pieces interfitting with each other in intersecting relation of the ring-shaped members when certain of the grooved portions of one of said members interfit with certain grooved portions of another of said members, there being at least three of said members disposed in mutually overlapping relation in the put-together position of said pieces, the space between certain companion interfitting grooved portions of two of said members being different than the space between certain other companion interfitting grooved portions of said members.

6. A puzzle of the put-together type comprising a plurality of puzzle pieces each of which is a ring shaped member having a radially extending peripheral rim, the rims of said members having interfitting portions in releasable engagement with each other, there being at least three of said ring shaped members which in the put-together position thereof are disposed in mutually overlapping relation.

7. A puzzle of the put-together type comprising a plurality of puzzle pieces each of which is a ring shaped member having a radially extending peripheral rim, the rims of said members having interfitting portions in releasable engagement with each other, there being at least three of said ring shaped members which in the put-together position thereof are disposed in mutually overlapping relation, at least one of said ring-shaped members having additional grooved portions which are not engaged by the other ring-shaped members in the put-together relation thereof, said additional grooved portions provided false clues to the solution of the puzzle, the engagement of one of said ring-shaped members in said additional grooves preventing the proper mutual interfitting of the three ring-shaped members.

8. A puzzle of the put-together type comprising a plurality of puzzle pieces each of which is a ring shaped member having a radially extending peripheral rim, the rims of said members having interfitting portions in releasable engagement with each other, there being at least three of said ring shaped members which in the put-together position thereof are disposed in mutually overlapping relation, the space between certain companion interfitting grooved portions of two of said members being different than the space between certain other companion interfitting grooved portions of said members.

IRVING STEINHARDT.
